UNITED STATES PATENT OFFICE

153,744

DESIGN FOR A MOBILE CARRIER FOR VACUUM CLEANER AND ACCESSORIES OR THE LIKE

John L. Zver and Martin G. Zver, Chicago, Ill.

Application November 15, 1947, Serial No. 142,564

Term of patent 14 years

(Cl. D14—3)

To all whom it may concern:

Be it known that we, John L. Zver and Martin G. Zver, both citizens of the United States and both residing in Chicago, in the county of Cook and State of Illinois, have jointly invented a new, original, and ornamental Design for a Mobile Carrier for Vacuum Cleaner and Accessories or the like, of which the following is a specification, reference being had to the accompanying drawing forming a part thereof.

In such drawing:

We claim:

The ornamental design for a mobile carrier for vacuum cleaner and accessories or the like, as shown.

JOHN L. ZVER.
MARTIN G. ZVER.
